US0D1041130S

(12) **United States Design Patent** (10) Patent No.: **US D1,041,130 S**
(45) Date of Patent: ** Sep. 10, 2024

(54) **SHOE**

(71) Applicant: **Lihong Wu**, Fujian (CN)

(72) Inventor: **Lihong Wu**, Fujian (CN)

(**) Term: **15 Years**

(21) Appl. No.: **29/933,264**

(22) Filed: **Mar. 19, 2024**

(51) LOC (14) Cl. **02-04**

(52) U.S. Cl.

USPC **D2/902**
